UNITED STATES PATENT OFFICE

2,454,330

POSITIVE GRID OSCILLATOR

John W. McNall, East Orange, and Alfred H. Laidig, Bloomfield, N. J., assignors to Westinghouse Electric Corporation, East Pittsburgh, Pa., a corporation of Pennsylvania

Application April 13, 1944, Serial No. 530,890

6 Claims. (Cl. 315—6)

1

This invention relates to positive-grid oscillators, also known as retarding field oscillators, and is directed to structural features of such an oscillator of particular applicability in the more generic disclosure of concurrently filed application of co-inventor herein J. W. McNall, Serial No. 530,889, filed April 13, 1944.

Electrode spacing having commensurate relation to electron transit distance between the phase shifts of the oscillation period, introduces problems of mounting, fabrication, adjustment, tuning, and so forth, not encountered in usual oscillators, especially when the period of oscillation chosen is in the ultra high frequency range. Broadly, the present invention is directed to the solution of the several problems enumerated.

More specifically, an object of the invention is to provide a hollow body resonant cavity positive-grid oscillator.

Another object of the invention is to provide for a grid between cathode and anode each electrically a part with the resonator wall but, as to D. C. potential, electrically separate from either cathode or anode.

A further object of the invention is to provide a resonator the wall of which, together with the cathode, anode and positive grid will constitute a self-contained oscillatory circuit capable of having a D. C. potential on the positive grid differing from that on the cathode and anode.

Yet another object of the invention is to provide in a resonant cavity construction of tube, a positive grid rigidly mounted and accurately spaced between a closely spaced cathode and selector grid.

A still further object of the invention is to provide for adjusting the spacings of cathode to positive grid, selector grid to positive grid and anode to selector grid.

Furthermore, the invention has an object to provide for resonant and tunable cavities external to the evacuate portion.

Other objects of the invention will appear hereinafter as the description proceeds, both by direct recitation thereof and by inference from the context.

Referring to the accompanying drawings in which like numerals of reference indicate similar parts throughout the several views:

Figure 1 is a longitudinal sectional view of a hollow body resonant cavity positive-grid oscillator embodying the broad concept of our invention;

Figure 2 is a cross-section thereof on line II—II; Figure 3 shows diagrammatically the approxi-

2

mate physical and electrical relation of electrodes;

Figure 4 is a longitudinal sectional view of a hollow body resonant cavity positive-grid oscillator which is tunable and wherein all electrodes are insulated for separate application thereto of D. C. potentials;

Figure 5 is a plan of Figure 4;

Figure 6 shows diagrammatically the approximate physical and electrical relation of electrodes of the construction of Figure 4;

Figure 7 is a longitudinal section of a further modified construction of hollow body resonant cavity positive-grid oscillator wherein resonant cavities external to the evacuated electrode region are provided;

Figure 8 is a cross-section on line VIII—VIII of Figure 7; and

Figure 9 shows diagrammatically the approximate physical and electrical relation of the electrodes of Figure 8.

In the specific embodiment of the invention illustrated in said drawing and giving attention initially to Figures 1 to 3, a hollow body resonant cavity positive-grid oscillator is shown wherein the hollow body 15 is all metal and constituted as a cylindrical outer wall 16 having disc-like end walls 17 and 18 sealed at the ends of the cylindrical wall. At the mid-part of and sealed to said end walls are collars 19, 20, respectively, which are re-entrant in the sense that they project into the hollow body coaxially therewith, so their inner ends are directed toward each other within the body, said ends being parallel to each other and to the end walls of the resonator. Said collars each have a part thereof, which may be termed an extension of the collar, which projects outwardly from the end wall of the resonator, each said extension having an appropriate seal therebeyond for maintaining internal vacuum in the resonator and collars.

Within the resonator body and carried by one collar 19 inwardly beyond the inner end thereof, is a cathode 21 the emitting surface whereof is disc-shaped and with the axis of the disc coaxial to the axis of the collar and resonator body, thereby positioning the emitting surface transverse to that axis. The body of the cathode is a metallic hollow body of revolution and consists of a cap 50 portion of cup shape, the closed end of which constitutes the aforementioned disc-shaped part of the cathode and at the periphery of which is a cylindrical flange 22. Said flange fits over and is secured to a cylindrical head 23 of a housing portion having a cylindrical torso 24 from the other

end of which legs 25 project. The head 23 approximates the diameter of the re-entrant collar 19, whereas the torso 24 is of less diameter and the legs 25 spread to engage the inside of said collar and are spot welded or otherwise secured thereto. The inside of said collar 19 may be provided with a forwardly directed shoulder 26 for engagement by the ends of said legs 25, thereby serving to locate the cathode emitting surface precisely parallel to the said shoulder, which is in turn parallel to the end of said collar.

This cathode structure is part of the wall of a resonant cavity, and the provision of head 22 substantially the same diameter as collar 19 and separated therefrom by only a narrow peripheral gap, obtains virtual continuity of surface for high frequency oscillation and negligible impedance thereto across the gap. The structure, on the other hand has a tendency to prevent heat flow from the cathode to said collar, aiding, therefore in maintaining desired cathode temperature. This same cathode construction is employed likewise in the other tube constructions hereinafter described.

A heater filament 21 is shown within the cathode body, said filament being mounted on lead-in wires 28 which extend to the exterior through a glass press 29 formed as part of a re-entrant glass stem 30. The rim of said stem is sealed to the end margin of a suitable metallic ring 31, the other end margin of which is secured, as by welding, to the margin of the end of the collar 19 protruding from the resonator body. Ring 31 is of material having substantially the same coefficient of expansion as the glass, a material manufactured under the trade name "Kovar," in accordance with disclosure in Patent 2,062,335 of December 1, 1936, to Howard Scott, being the one preferred.

The other collar 20 is shown as having a grid 32 across the inner end thereof, this grid being distinguished herein from subsequently described grid by referring to it as the selector grid. Said selector grid is parallel to the cathode emitting surface and otherwise fulfills the requirements therefor as explained at length in said concurrently filed application.

Within said collar 20, spaced from the wall thereof and spaced from and parallel to said selector grid 32 is an electrode 33, which in the figure being described, is utilized as an anode. As here shown, said electrode 33 is in the form of a disc coaxial with the axis of the collar and resonator body and has a metallic stem 34 extending lengthwise of the collar and projecting from the outer end thereof for lead-in purposes. A dome-like glass seal 35 is sealed to the stem 34 next the outer end thereof, the rim of the dome being sealed to a ring 36 in turn sealed, as by welding, to the said collar. Ring 36 may conveniently be a duplicate in size and material of ring 31 at the cathode end of the device.

In parallelism to and between the aforementioned selector grid and cathode, is another planar grid 37, herein distinguished for reference purposes by the appellation thereto of the title of positive grid. This positive grid 37 extends outwardly beyond the cylindrical region between said cathode and selector grid and toward the cylindrical wall 16 of the resonator body. A plurality of supporting prongs or wires 38 project radially inwardly through said wall in the plane to said positive grid and have soldered or other attachment to said positive grid so as to rigidly mount the same in place. Said wires or prongs

38 are coaxially sealed, as by glass beads 39, within tubes 40 soldered or otherwise secured in appropriate holes in the said cylindrical wall. This construction affords adequate insulation and support for the grid and also provides a vacuum seal for the hole and wire. One of said wires may be utilized as an electrical connection for application of desired potential to the said positive grid. To prevent high frequency radiation from leaking out by way of said wires, a suitable choke 41 is applied to each.

Capacity coupling between the positive grid and the resonator wall for high frequency conduction continuity and for rendering the chamber resonant is provided in the form of cylindrical shells 42 spaced from the walls of the resonator body, a distance adequate to prevent passage of D. C. potential. These shells are coaxial with the resonator cylindrical wall and have inturned flanges 43 next the positive grid, said flanges being juxtaposed upon and secured to the said grid. Support for the said shells is obtained by the same radially disposed wires 38, which support the attached positive grid. From the construction shown of parallel and close association of cylindrical shells 42 to the cylindrical resonator wall 16, continuity for high frequency oscillation is provided and at the same time discontinuity for D. C. current flow is obtained. A coaxial line output 44 the center conductor of which loops into the resonator chamber is provided as usual with hollow body high frequency resonators.

Electrode spacing and connections are dealt with more fully in the said concurrent application, for use of the device as a positive grid oscillator. Suffice it to say herein that, as indicated by Figure 3, the spacing of the several electrodes is related to electron transit time and here shown as such that an electron may travel from cathode 40 21 to positive grid 37 and from positive grid 37 to selector grid 32 substantially in the time required for oscillating phase shift of 180° each. Also spacing of the anode from selector grid 32 is substantially a distance representing transit time 45 of an electron therebetween during a 90° phase shift so the electron makes the round trip from said selector grid, to the anode and back to the selector grid during substantially a 180° oscillating phase shift. Because of the metallic continuity from cathode mounting to selector grid mounting, those electrodes are shown in Figure 50 3 as connected. Other relationships and character of electrodes may, however, be provided as found desirable or to carry out the operation of 55 the device in any manner, such as described in said concurrently filed application.

While Figures 1 to 3 illustrate the fundamental inventive concept, it is within the scope of the invention to vary the spacings and electrical connections of the electrodes as found desirable. Furthermore, it may be stated that the electrode referred to herein as the anode occupies the position usually ascribed to an anode, and the term is thus used to distinguish it from other electrodes without restriction as to the functioning thereof. Said anode may be utilized for receiving electrons, may be utilized for reflecting primary electrons, or may be used to emit secondary electrons, and to indicate more definitely this inclusive characterization, may be more generally referred to as an electron-pulling electrode.

In Figures 4 to 6, structure embodying the invention is shown wherein all electrodes are electrically insulated one from another and wherein the several electrodes have adjustment for spac-

ing thereof from the positive grid electrode, the anode likewise being adjustable in its spacing with respect to the selector grid.

Describing the embodiment of Figures 4 to 6 more in detail, a hollow body resonator chamber 45 is shown having a cylindrical wall divided midway of its length, thereby providing aligned, but spaced, cylindrical wall sections 46, far ends of which are closed by end walls 47. Re-entrant within and coaxial with each cylindrical section, extending from, and here shown integral with, the end wall of each section, is a hollow collar, the one for the cathode being identified by numeral 48 and the opposite one for the selector grid and anode being designated by numeral 49. The inner ends of these two collars are directed toward each other within chamber 45 and said ends are parallel to each other and to the end walls of the said chamber. A cathode 21 as previously described with cylindrical flange 22 on a head 23 of a housing having cylindrical torso 24 and legs 25, limited in position by shoulder 26 is carried by collar 48, the cathode, of course, having a heater 27 (see Fig. 6).

At the outside of end wall 47 having collar 48 is a virtual extension 48a of said collar to which a metallic ring 31 is secured by welding an end margin within said collar, the other end of said ring being sealed by the flare portion of re-entrant glass stem 30.

The other collar 49 is traversed at its inner end by selector grid 32 as in the construction previously described, said grid being secured to the collar and situated in parallel spaced relation to the cathode. Within said collar, spaced from the wall thereof and spaced from and parallel to said selector grid 32, is, using the term broadly, an anode 33 having a metallic stem 34a extending lengthwise of the collar and projecting beyond the far end thereof. In the present showing said stem is made longitudinally adjustable, thereby enabling the anode to be moved toward and away from the selector grid.

Support for the stem 34a is from the resonator end wall 47 at the outside of which protrudes a virtual extension 49a of collar 49, a metallic ring 36 being welded or otherwise secured to said collar. The outer end of said ring has a glass collar 50 sealed thereto and to the far end of the glass collar is another ring 51, which in turn has secured vacuum tight at its far end an annulus 52 screw threaded at its outside and connected vacuum tight at its inside to the said stem by a flexible diaphragm 53. Outside the threaded annulus is an internally threaded knob 54 having an end wall rotatable upon the stem and engaging a shoulder 55 formed on the stem. Outward displacement of the knob longitudinally of the stem is prevented by a cap 56 held on the said stem by a set screw or otherwise as found desirable. The outside of said knob is provided with an insulating covering 57 to avoid subjecting the operator to potential applied to the stem by way of cap 56 which is conveniently used as a contact terminal.

In the showing of Figure 4, the end walls 47 for the resonator body are made movable with respect to the positive grid 37. As in the previously described construction, said positive grid extends between the cathode 31 and selector grid 32 parallel thereto and radially outward to the vicinity of the cylindrical side wall of the resonator, and in this instance is shown projecting between the facing ends of the side wall sections. Capacity coupling between said positive grid and the reso-

nator wall sections for high frequency conduction continuity and for rendering the chamber resonant is provided, as before, in the form of cylindrical shells 42a spaced each from one said resonator wall section a distance adequate to prevent passage of D. C. potential. These shells are coaxial with the respective sections of the resonator within which situated, and are shown with outward flanges 43a next the positive grid, said flanges being juxtaposed upon and secured to the said grid at its peripheral margin. Support for said grid and shells is obtained by use of radial wires 38, which are introduced through glass seals 39a in this instance formed integrally with a glass ring 58 coaxially situated around, but spaced outwardly from the periphery of said positive grid 37 and outside and spaced from resonator wall sections 46. At top and bottom edges of this glass ring in virtual continuation thereof are metallic rings 59 having substantially the same coefficient of expansion as the glass ring and preferably of the aforementioned "Kovar." At the margin of each said metallic ring 59 remote from the margin sealed in the glass, is secured, as by welding, an annulus 60 the outer periphery of which is screw threaded and receives a threaded collar 61, the other end of which is flanged inward, as at 62, to overlie the end wall 47 of the resonator. The outside of this collar 61 is covered with insulation 63 that it may be grasped and operated with immunity to electrical shock to the operator. Between said annulus 60 and end wall 47 a flexible member or bellows 64 is secured vacuum tight, said bellows preferably exerts resilient pressure longitudinally or axially thereof, thereby tending to separate the end wall 47 from the annulus 60 when unscrewing the collar 61. The selector grid mounted on re-entrant collar 49 from end wall 47 is thus adjustable with respect to the positive grid 37, and similarly cathode 21 is independently adjustable with respect to said positive grid. The construction accomplishes a support of each electrode electrically insulated from support for all other electrodes.

While the constructions so far described utilize hollow body resonators which are included within the evacuated region, the invention also contemplates the use of resonators exterior to the evacuated region. Such a construction is shown by Figures 7 to 9, wherein the evacuated region is confined to a cartridge-like enclosure. As shown, the construction is substantially an adaptation of the collars 19 and 20 of Figure 1, providing a glass seal between the collars, said seal supporting the positive grid.

Describing the showing of Figures 7 to 9 more in detail, axially aligned metallic collars 66, 67 are provided the facing ends of which are parallel. One of these collars, 66, supports a cathode 21 in front thereof in accordance with descriptions heretofore given in connection with constructions of the other figures of the drawings, and corresponding reference numerals from Figure 1 are applied without repetition of the description. Similarly, the other collar 67 has a selector grid at its inner end and contains an electrode (for distinguishing purposes again called an anode) supported by a stem sealed through a glass dome, and reference numerals from Figure 1 are again applied without repetition of description. Difference in the collars from the showing of Figure 1 exists in the provision of radial flanging or enlargement of said collars at 68 in the vicinity of sealing of the "Kovar" rings 31 and 36 thereto. Virtual extensions 69 of said collars project

from the said enlargements in directions away from each other and coaxially to and around said rings. Projecting toward each other from said enlargements and situated around said collars are glass rings 70 for insulating and sealing purposes. The outside diameter of these glass rings is substantially the same as for the extensions 69. A washer-like conductive plate 71 has its inner margin situated between and sealed to the contiguous ends of the glass rings 70, said plate extending radially outward from said rings and having an outer peripheral cylindrical rim 72 thereon the outer face whereof is screw threaded. The inner margin of the said plate next the said rings has the positive grid 37 secured thereto, said grid being situated between and parallel to the cathode and selector grid.

The said collars 66, 67 and their extensions 69 constitute inner cylindrical walls for an annular resonator chamber 73, the outer wall of which is composed of cylindrical sections 74 having contiguous ends flanged, as at 75, and seated against plate 71 within rim 72 thereof. Clamping nuts 76 on the said rim engaging the outer flat faces of said flanges clamp the said sections in axial alignment coaxially to the inner wall of the resonator.

The outer ends of the resonator chamber are closed with insulating spacers 77. Within the chamber 73 next each outer end thereof is an inwardly facing piston 78 having sliding contact with one cylindrical wall of the resonator and having capacitative relation to the other cylindrical wall thereof so as to pass high frequency current but prevent passage of the D. C. low potential. Arbitrarily we show contact of the piston with outer wall 74 and capacitative relation to wall 69 but this arrangement may be reversed if desired. Each piston is carried by a plurality of plunger rods 79 which extend outwardly through the spaces 77 and are attached to a wheel-like controlling handle 80. An output coupling 44 is provided as before, to take advantage of the generated power.

Spacing of the electrodes and constitution of the so-called anode as electron receiving, reflecting or multiplying may be carried out in accordance with the disclosure of said concurrently filed application, wherefore specific showing of spacing of electrodes in Figures 3, 6 and 9 herein is to be considered illustrative rather than restrictive.

It will be noted with respect to all showings herein that special care has been taken of making parts on opposite sides of the positive grids as nearly identical as possible, thereby reducing the number of different parts to be fabricated, and lowering cost of tools, dies and fixtures in manufacture of the device.

We claim:

1. An electronic device comprising a cylindrical outer wall having end walls, said cylindrical outer wall and end walls forming a hollow enclosure, collars projecting from said end walls toward each other within said enclosure coaxial with said cylindrical outer wall, an electron-pulling electrode within and next the inner end of one of said collars and electrically insulated therefrom, a grid fixed to the electrode-containing collar in spaced parallelism to said electron-pulling electrode, a second grid parallel to and spaced from the first said grid and having a part therefrom projecting radially through the said cylinder, and a cathode parallel to and on the opposite side of the second grid from the first

grid and axially aligned with said electron-pulling electrode for directing electrons through the said grids toward said electrode.

2. An electronic device comprising a cylindrical outer wall having end walls, said outer wall and end walls forming a hollow enclosure, a grid transverse to said cylindrical outer wall and parallel to said end walls dividing said enclosure substantially in half and forming the said enclosure into two resonators, collars projecting from said end walls toward each other and toward said grid and coaxial to and within the respective resonators and forming inner cylindrical walls therefor, an electron-pulling electrode within and electrically insulated from one said collar, a cathode carried by the other said collar, and capacitative coupling in the electrical circuit between said grid and collar and interposed between said outer cylindrical wall and said inner cylindrical walls of each resonator for providing continuity of circuit for high frequency and interposing thereby interruption to circuit path for low frequency current from said grid to said collars.

3. An electronic device comprising a pair of aligned cylinders, end walls at the outer ends of said cylinders, a fixed grid transverse to the axis of said cylinders and at a plane between inner ends of said cylinders, said grid having a peripheral portion projecting between said inner ends of the cylinders, collars coaxial with said cylinders and projecting toward each other and toward said grid from said end walls, a grid at the inner end of one of said collars, said grids being parallel to each other, an electron-pulling electrode within the collar having the grid, and a cathode carried by the opposite collar from the one having said electrode therein, said cathode having electrical continuity with the collar carrying the same, and one of the grids having electrical continuity with the other of said collar.

4. An electronic device having a cathode and an opposed electron-pulling electrode and having a hollow body resonator, re-entrant coaxial collars therein, the inner ends whereof are directed toward each other, said hollow body resonator comprising an outer shell in electrical continuity with said collars and providing an inner shell capacitative coupled with respect to the outer shell, thereby providing high frequency electrical continuity, and a grid physically and electrically joined to the said inner shell and situated between the said inner ends of the re-entrant coaxial collars.

5. An electronic device having a cathode and an opposed electron-pulling electrode and having a hollow body resonator having end walls, means providing electrical discontinuity of one end wall to the other, each of said end walls having an outer shell section as part of the resonator body and each having a re-entrant collar within said shell section, an inner shell capacitative coupled with respect to both said outer shell sections, and a grid physically and electrically joined to the said inner shell and situated between the said outer shell sections and said re-entrant collars out of electrical contact therewith.

6. An electronic device comprising coaxial collars having ends directed endwise toward each other, one having a cathode at its end and the other having a grid at its end, said collars each having an enlargement thereon, a second grid between said ends of the collars, insulating rings between said enlargements and said second grid supporting said second grid and sealing the in-

terior region of said collars, said collars constituting inner walls of a hollow body resonator, an electron-pulling electrode opposed to said cathode, an outer wall for said hollow body resonator, and movable plungers between said inner and outer walls constituting end walls for said resonator for tuning said resonator.
